(57) **CLAIM**

The ornamental design for a luminaire, as shown and described.

DESCRIPTION

FIG. 1 is a perspective view of our new luminaire;
FIG. 2 is a second perspective thereof;
FIG. 3 is a top view thereof;
FIG. 4 is a bottom view thereof;
FIG. 5 is a right view thereof, a left view being a mirror
image thereof;
FIG. 6 is a front view thereof; and,
FIG. 7 is a back view thereof.
The broken lines in the drawings illustrate portions of the
luminaire which forms no part of the claimed design.
